UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WILLIAM McCALLUM, OF SAME PLACE.

DESIGN FOR CARPET.

Specification forming part of Design No. 7,094, dated January 6, 1874; application filed December 27, 1873.
[Term of Patent 3½ years.]

K.

To all whom it may concern:

Be it known that I, ALFRED HEALD, of Philadelphia, Pennsylvania, have invented a Design for a Carpet-Pattern, of which the following is a specification:

The figure in the accompanying drawing represents sufficient of a carpet-pattern to clearly illustrate my design, the remainder of the pattern being merely a repetition of that which appears.

The pattern is composed, mainly, of bands or ribbons A, crossing each other at right angles, so as to inclose square or diamond-shaped spaces, in each of which is an ornamental figure, a, of a circular, or nearly-circular, outline. Each band A is bounded, at its opposite

sides, by a zigzag edging, b, and the interior of the said band is ornamented by flowers, leaves, and stems, arranged as shown.

Irrespective of colors employed, I claim—

The design for a carpet-pattern, consisting of ornamental bands A, crossing each other at right angles, and inclosing spaces occupied by figures a, as set forth, and shown by the accompanying drawing.

In testimony whereof I have signed my name to this specification in the presence of two subscribing witnesses.

ALFRED HEALD.
